UNITED STATES PATENT OFFICE

2,607,086

REFRIGERATOR DOOR CONSTRUCTION

Ralph Saunders, Esher, England

Application June 23, 1948, Serial No. 34,626
In Great Britain July 17, 1947

5 Claims. (Cl. 20—35)

1

This invention relates to thermally insulated chambers such as refrigerators, cold storage chambers and the like. It is, of course, well known that, in the case of domestic and other refrigerators, cold storage chambers and the like, there is a considerable temperature difference on opposite sides of the door, which temperature difference may be 70° or even more, particularly where the deep freezing process is in use. Heretofore the joint around the door has been made by means of one or more rubber or like gaskets which are pressed into contact with the door frame and with a not inconsiderable pressure. With refrigerators, cold storage chambers and the like as previously constructed, trouble has been experienced from the fact that when the door is opened moisture condenses around the door frame, which moisture, after the door is closed, turns to ice with the result that the gasket or gaskets is or are frozen to the door frame. Considerable force will then be necessary to open the door which is often damaged or distorted in the process. The chief object of the present invention is to overcome this disadvantage.

According to the main feature of the present invention, the door when closed is adapted to define a closed chamber or peripherally extending space around its edge between the inside and outside of the refrigerator, cold storage chamber or the like, and means are provided for maintaining said chamber at a temperature above freezing point.

Conveniently the door, when closed, is adapted to form two such chambers between its edge and the door frame.

According to another feature of the present invention, the use of rubber or like gaskets is dispensed with and a metal to metal joint is employed between the door and the door frame. In this case, and particularly where the frame of the door and the door frame are in the form of metal castings, it is desirable to use a metal of low thermal conductivity such as magnesium or a magnesium alloy. Also where the frame of the door and the door frame are metal castings, it is necessary to make the frames in two parts which are heat-insulated from one another in order to prevent the conduction of heat from the outside to the inside of the chamber.

In order that this invention may be the more clearly understood and readily carried into effect reference may be made to the accompanying drawings which illustrate, by way of example, one convenient embodiment of the present invention and in which:

Figure 1 is a front elevation of an insulated door and framing according to the present invention.

Figure 2 is a section on line 2—2 of Figure 1 and,

Figure 3 is a section on line 3—3 of Figure 1.

Referring now to the accompanying drawings, in the embodiment of the present invention therein illustrated the door frame 10 and the framing 11 of the door itself are made in the form of castings of a metal of low thermal conductivity, such as magnesium or a magnesium alloy. The door 10 itself is lagged with cork or other suitable material in any desired manner as at 12, this forming no part of the present invention and the chamber is similarly lagged, see 13. It follows that as the door frame 10 and the framing 11 of the door itself are made of metal or other thermally conductive material, some means must be provided for preventing the conduction of heat from the outside to the inside of the refrigerator, cold storage chamber or the like, and with this object in view the door frame 10 and the framing 11 of the door are each made in two parts, a front or exterior part and a rear or exterior part, (as shown in Figures 2 and 3) and a strip of heat insulating material 14, such for example rubber or the material sold under the trade-mark "Tufnol," or other resilient thermally insulating material is inserted between the two parts, which are, of course, suitably held together to form the complete frames.

The framing 11 of the door is substantially semi-circular in cross-section and the door framing 10 may also be regarded as being of circular shape in cross-section as will be seen from the drawings. The door frame 10, however, is provided around its front with a bead 15 which may be substantially circular in cross-section and the framing 11 of the door is provided at the rear with an annular bead 16. The parts are so proportioned that with the door closed the bead 15 on the door frame 10 contacts with the framing 11 of the door and, also, the back of the door frame 10 contacts with the bead 16 on the framing 11 of the door. In addition to the front and back contacts between the door frame and the framing of the door, the two heat insulating strips 14 in the frames likewise contact each other (see Figures 2 and 3). The door when closed thus serves to define two closed chambers or spaces 17 and 18 which extend peripherally all around its edge. By making the frames of a metal or allow or other thermally conductive material such as that referred to above it is

easy to secure air-tight joints where the parts are in direct contact without the use of high pressures such as are necessary when rubber or like gaskets and wooden frames are used. Furthermore, the strength of the metal frames is such that there will be no tendency of the same to distort so that air-tight joints will always be maintained.

Now it will be appreciated that with metal to metal joints such as those described above the tendency of the joint to freeze up due to the condensation of moisture when the door is opened is considerably enhanced. In order to avoid all possibility of the door freezing up, means are provided for heating the air within the closed chambers defined by the door when closed to a temperature above freezing point. Any suitable means may be employed for heating the air within the closed chambers without departing from the scope of the present invention. For example, low temperature electrical heaters 19 may be employed and they may be thermostatically controlled. The air within the two closed chambers 17 and 18 may be heated to the same temperature or to different temperatures as desired.

Means may be provided for draining away any moisture which condenses in the closed chambers.

The circular bead 15 all around the edge of the front of the door serves not only to provide one of the joints between the door frame and the framing for the door but, also serves as a convenient means of hinging the door (see 20) and carrying the fastening means (not shown).

If desired, the door, when closed, may be adapted to define only a single closed chamber, or more than two closed chambers around its edge without departing from the scope of the present invention.

Also, whilst it is preferred to make the frames of metal and to dispense with the use of gaskets, the feature of the present invention whereby the door when closed defines one or more closed chambers around its edge, which chamber or chambers is or are heated to a temperature above freezing point, may also be usefully applied to wooden, plastic or other doors with the joints formed of rubber or like gaskets or, in some cases, without gaskets.

I claim:

1. A thermally insulated chamber of the class described, said chamber having an opening therein, comprising: a door frame of thermally conductive material mounted in said opening and

comprising interiorly and exteriorly disposed portions thermally insulated from each other; a door comprising a framing of thermally conductive material hingedly mounted in said door frame, said framing comprising interiorly and exteriorly disposed portions thermally insulated from each other, said door frame and said framing of said door being shaped for direct contact therebetween at the interior and exterior portions thereof and defining a peripherally extending space therebetween when the door is closed; and a heater disposed in said peripheral space, for maintaining the temperature in said space above the freezing point.

15 2. A thermally insulated chamber according to claim 1 in which the interiorly and exteriorly disposed portions of the said door frame and said framing of said door are thermally insulated from one another at the peripheral portions thereof, each by a strip of resilient thermally insulating material, the arrangement being such that when the door is closed said strips engage each other dividing said peripheral space into two portions interiorly and exteriorly disposed with respect to each other.

20 3. A thermally insulated chamber according to claim 2 wherein said heater comprises at least one low temperature electrical heater disposed in one of said portions of said peripheral space.

4. A thermally insulated chamber according to claim 3 wherein the two portions of said peripheral space are heated to different temperatures.

5. A thermally insulated chamber according to claim 3 wherein said low temperature electrical heater is thermostatically controlled.

RALPH SAUNDERS.
